US00D399964S

United States Patent [19]

Katayama et al.

[11] Patent Number: Des. 399,964

[45] Date of Patent: **Oct. 20, 1998

[54] BIOCHEMICAL ANALYSIS MACHINE

[75] Inventors: **Atsushi Katayama**, Kokubunji; **Hiroyuki Kuriyama**, Tokyo; **Hirosi Mitsumaki**, Mito, all of Japan; **Peter Hohmann**, Milan, Italy

[73] Assignee: **Hitachi, Ltd.**, Tokyo, Japan

[**] Term: 14 Years

[21] Appl. No.: 78,482

[22] Filed: Oct. 14, 1997

[30] Foreign Application Priority Data

Apr. 11, 1997 [JP] Japan 9-50793

[51] LOC (6) Cl. 24-01

[57] CLAIM

The ornamental design for a biochemical analysis machine, as shown and described.

DESCRIPTION

FIG. 1 is a front, top and right side perspective view of a biochemical analysis machine showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.
